UNITED STATES PATENT OFFICE.

HARRY GLABERMAN, OF BROOKLYN, NEW YORK, ASSIGNOR TO NATIONAL FORM & FIXTURE CO., A COPARTNERSHIP COMPOSED OF HARRY GLABERMAN AND SAMUEL SILVERMAN, OF BROOKLYN, NEW YORK.

DESIGN FOR A BASE FOR DISPLAY FIXTURES OR SIMILAR ARTICLES.

Application filed August 3, 1927. Serial No. 22,986. Term of patent 7 years.

To all whom it may concern:

Be it known that I, HARRY GLABERMAN, a citizen of the United States, and a resident of New York city, borough of Brooklyn, in the county of Kings, and State of New York, United States of America, have invented a new, original, and ornamental Design for a Base for Display Fixtures, or Similar Articles, of which the following is a specification, reference being had to the accompanying drawing, forming part thereof.

The drawing is a perspective view of a base for display fixtures or similar articles showing my new design.

I claim:

The ornamental design for a base for display fixtures or similar articles substantially as shown.
